BARRETTE

Nathan L. Solomon, Mount Vernon, N. Y.

Application April 16, 1938, Serial No. 202,368

6 Claims. (Cl. 132—48)

The subject matter of this invention is an improved and serviceable hair clasping barrette of the type having a longitudinally curved hollow bar adapted to be initially set on the top surface of the hair to be clasped and including a loop swingably connected to one end of the bar and adapted to be inserted under the hair and constituting means cooperating with a spheroidal shaped protuberance depending from another end of the bar for disengageably locking the loop to the bar. One object of the invention is realized in the provision of a barrette of the character referred to wherein the bar includes spaced and depending rows of teeth adapted to initially divide the hair to be clasped into several strands and wherein the teeth of the spaced rows of teeth are disposed in a staggered relation to prevent slippage of the bar longitudinally of the hair to be clasped after the bar has been set and applied to the hair. The invention has as another object the provision of a barrette of the character referred to wherein the loop is formed from wire and comprises an expanded portion for staying the hair, a reduced portion adapted to disconnectably engage the protuberance depending from the bar, and a terminal eye defined by crossed and superimposed arms of the loop at one end thereof, the eye being swingably associated with the bar and includes ends pivotally carried by a socket sustained by the bar. The invention has as a further object the provision of an improved and ornamental barrette characterized by a longitudinally curved bar having a plurality of perforations each bounded by a plurality of prongs serving as means to hold ornamental effects in spaced relation to the rim of a respective perforation to permit air currents to flow into and out of the bar to facilitate drying of the clasped hair. Other objects, features and advantages of the invention will appear from a consideration of the following detailed description taken in connection with the accompanying drawing in which:

Fig. 1 is a plan view of the barrette according to my invention.

Fig. 2 is an underneath view of Fig. 1.

Fig. 3 is a side view of Fig. 1.

Fig. 4 is a sectional view taken on the line 4—4 of Fig. 3.

Fig. 5 is a sectional view on the line 5—5 of Fig. 3.

Fig. 6 is an enlarged fragmentary and underneath view of Fig. 3 however illustrating the arms of the loop staying the several tresses set

by the staggered teeth of the opposed rows of teeth.

Fig. 7 is an enlarged and fragmentary view of Fig. 5 and

Fig. 8 is a fragmentary portion of the bar 5 before the prongs are bent outwardly thereof. The hair clasping barrette B comprises a hollow bar 11 and a swingable loop 12. Bar 11 includes a longitudinally curved top 13 having downward and inwardly curved edge portions 14 10 each integral with a horizontally arranged wall 15 each provided with a depending part 16 having a plurality of teeth 17, the teeth of the depending parts 16 constituting two spaced rows of teeth disposed longitudinally of the bar with 15 the teeth of one of the rows disposed in staggered relation with the teeth of the opposing row as shown in Figs. 3 and 6.

When the bar is positioned on the head of hair several strands of hair are disposed between the 20 adjacent teeth of the opposing rows of teeth and since the teeth of the opposing rows are staggered, the several strands are in part divided to form flared portions F which in turn cooperate with the teeth thus preventing displacement of 25 the bar longitudinally of the hair to be clasped.

The wire loop 12 comprises spaced arms 18 having a closed and reduced end 19 and an eye E, and for purposes of specification the part of the loop between the eye E and the closed reduced end 19, may be considered as the normally expanded part thereof.

It will be noted that the arms 18 are provided with the inclined portions 21 each merging with a part 22 having an inwardly turned terminal 35 23, that is, arms 18 are bent, crossed, and superimposed to define the eye E characterized by inclined portions 21, sides or parts 22, and the terminals 23.

The terminals 23 are pivotally sustained in 40 socket 24 carried at one end of the bar and the reduced and closed part 19 of the loop is adapted to be pressed against depending rounded protuberance 25 and over the latter to be received and interlocked with the spaced grooves 26 45 above the spheroidal shaped protuberance 25.

With the bar positioned on the head of hair, the loop is swung underneath the hair and in order to stay or hold the hair between the bar and loop, the reduced part 19 of the latter can 50 be readily interlocked with the bar as explained. However as the attenuated part of the loop snaps over protuberance 25, the expanded part of the loop dilates slightly, causing a certain stress to be imparted to the eye through the crossed and 55

inclined portions 21 which may be secured together by solder if desired. The stress thus imparted to the eye of the loop has normal tendency to urge terminals 23 towards each other, thus preventing accidental removal of the eye from socket 24 even if the crossed portions 21 were not directly secured.

In assembling the loop to the bar, the arms 18 are moved towards each other, thus separating terminals 23, permitting the latter to be properly positioned in respect to socket 24. Thereafter manual pressure is removed from arms 18 and the latter are automatically diverged and the terminals 23 enter the opposed ends of socket 24. Following this step, the inclined and crossed portions 21 may be fixedly secured together.

To facilitate drying of the hair clasped between the bar and loop, the bar is provided with a plurality of slots 29. These slots define a plurality of prongs or fingers 30 which are bent upwardly and crimped to constitute a setting or seat for supporting an ornamental stone 31, the seat thus formed holds the widest part of the stones away from the top surface of the bar and consequently air may flow through or out of the slots 29 and through or out of the openings formed in the bar after the prongs have been bent outwardly and upwardly.

While the principles of the invention have been shown and described in connection with a preferred embodiment thereof, the features of which have also been disclosed in detail, it is to be understood that this has been done for purposes of disclosure only and that the invention is not limited thereby but is susceptible to various changes in form and detail of its scope.

I claim:

1. In a barrette, a longitudinally curved bar having spaced and depending rows of teeth with the teeth of said rows disposed in staggered relation; a loop comprising crossed arms and constituting an eye swingably carried by said bar, a closed and reduced part, and an expanded part intermediate said eye and reduced part; and a grooved protuberance depending from said bar and adapted to disengageably interlock with said reduced part.

2. In a barrette, a longitudinally curved bar having spaced and depending rows of teeth with the teeth of said rows disposed in staggered relation, a grooved protuberance depending from said bar, a socket carried by said bar; and a loop comprising a reduced portion for disconnectably

interlocking with said protuberance, an expanded portion to prevent downward displacement of hair interposed between said bar and loop, and inwardly turned terminals swingably carried by said socket.

3. In a barrette, a longitudinally curved bar having spaced and depending rows of teeth with the teeth of said rows disposed in staggered relation, a rounded and grooved protuberance depending from one end of said bar, a socket carried by another end of said bar; and a loop comprising spaced arms constituting a reduced portion for resiliently interlocking with said protuberance, an expanded portion to prevent downward displacement of hair interposed between said bar and loop, and inwardly turned terminals swingably carried by said socket.

4. In a barrette, a longitudinally curved bar having spaced and depending rows of teeth with the teeth of said rows disposed in staggered relation, a grooved protuberance depending from said bar, a socket carried by said bar, and a loop comprising spaced and curved arms constituting a reduced and closed portion for resiliently interlocking with said protuberance, an expanded portion to prevent downward displacement of hair interposed between said bar and loop, and inwardly turned terminals swingably carried by said socket.

5. In a barrette, a longitudinally curved bar having spaced and depending rows of teeth with the teeth of said rows disposed in staggered relation, a grooved protuberance depending from said bar, a socket carried by said bar, and a loop comprising crossed and fixedly connected superimposed arms and defining a reduced portion for resiliently interlocking with said protuberance, an expanded portion to prevent downward displacement of hair interposed between said bar and loop, and inwardly turned terminals swingably carried by said socket.

6. In a barrette, a longitudinally curved perforated bar having spaced and depending rows of teeth with the teeth of said rows disposed in staggered relation, a grooved protuberance depending from said bar, a socket carried by said bar, and a loop comprising spaced arms, said arms being in part crossed and disposed in overlapping relation and constituting an eye having inwardly turned terminals pivotally sustained by said socket, said loop having a reduced portion for disconnectably engaging said protuberance.

NATHAN L. SOLOMON.
